UNITED STATES PATENT OFFICE

FRANKLIN N. ROPP, OF HOLLYWOOD, CALIFORNIA

COMBINATION JOIST HANGER AND TIE

Application filed December 17, 1928. Serial No. 326,560.

This invention relates to combination joist hangers and ties, and the principal object is to provide a simple, economical and efficient device embracing a hanger formed of an integral piece of sheet metal and adapted to be supported on and anchored in a concrete wall for carrying the end of a joist, together with means attachable to the joist and connected with the hanger in such a manner that movement of the joist relative to the wall in any direction will be prevented.

With the above and other objects in view, I have shown a preferred form of device in the accompanying drawings, in which Fig. 1 is a fragmentary sectional elevation of a wall and a floor joist anchored thereon by means of my improvements.

Fig. 2 is a sectional plan of the same.

Fig. 3 is a perspective view of a tie bar adapted to have inter-locking engagement with the joist hanger.

Fig. 4 is a perspective view of a special and improved form of hanger forming part of my improvements.

Various and sundry means have heretofore been provided for supporting the floor joists at their ends on concrete and brick walls, but the usual means provides only for supporting the joists and do not prevent the movement of the joists vertically and longitudinally relative to the wall.

I have shown and will now describe means, by particular reference to Figs. 3 and 4 of the drawing, whereby the joists may be so supported that they will be bonded or tied to the walls and will prevent movement relative thereto.

My improvements embody primarily a special form of hanger H, shown in Fig. 4, and a special form of tie bar B, shown in Fig. 3. The hanger is formed of an integral piece of sheet metal, preferably wrought iron, is of U-shaped cross section of a width corresponding to the thickness of the joist to be carried there-in, and is of such a form that portions thereof may be imbedded in the wall for anchoring the hangers and joists permanently thereto.

The hangers H have parallel sides h and h1 connected at their lower extremities by means of a web h2 with continuing inclined and

rearwardly disposed upper portions h3, h3 which are bent inwardly at right angles at h4, h4 at their extremities. The web h2 and triangular portions h5, h5 of the sides extend inwardly into the wall W, as do also the portions h3 and h4. The portions h5 and the web h2 serve to support the hangers in the wall in the plane of the web, while inwardly bent portions h6 from the sides h and h1 are adapted to abut the face of the wall, as shown in Fig. 1. The portions h4, h4 at the inner extremities of the sides serve as anchors to receive the downward thrust of the joist J in connection with the portions h5. One or both of the sides h and h1 may be provided with outwardly bent lugs h7 and h8, as shown in Fig. 4, which are adapted to receive there-between the downwardly bent ends b of the tie bar B.

The form and position of the lugs h7 and h8 is such that the outer curved portion b2 of the bar B will engage the lug h7, while the inner curved portion b1 will engage the lug h8, as shown in Fig. 1. The bar B, when de-tached from the joist J may be rotated downwardly, as seen in Fig. 1, for disengaging the edges b2 and b1 from the lugs h7 and h8. The bar B is attached to the hanger H by a reverse movement and may then be permanently attached to the joist J by means of a plurality of bolts, nails or lag screws, as at B', B', inserted through apertures b', b'.

It will be observed that the portion b of the tie bar is bent outwardly, as shown in Fig. 2, to clear the side h1 of the hanger.

In operation the hangers H are initially supported by suitable means on the form for the wall W and the concrete is poured around the anchoring portions h4 and h5 of the hangers so that when the wall is set and the forms are removed the position of the hangers will be substantially the same as shown in Fig. 1.

In such position the hangers will be firmly imbedded and anchored in the concrete of the wall and will be supported thereon rigidly enough to firmly hold the joists J against displacement. The bars B are then swung into interlocking engagement with the hangers by inserting the portions b thereof

between the pairs of lugs h_7 and h_8 on the hangers. Thereafter the bars B may be attached to the joists by means of the bolts B' or otherwise.

5 The joists J being rigidly connected with the hangers H and said hangers being rigidly anchored to the wall W, the joists will be immovably fixed in their positions relative to the wall and a firm rigid structure will be provided. Such means of tying the joists to the anchored hangers in the walls renders a building more proof against damage by reason of earthquakes and the action of the elements than would otherwise be possible.

10 15 What I claim is:

1. A joist hanger comprising a U-shaped member adapted to rest against the face of a wall and provided with horizontal and vertical anchor portions at the base thereof adapted to be imbedded in a wall, and projections from the sides extending upwardly and rearwardly into the wall and bent at angles therefrom for providing additional anchor portions above said base.

2. A joist hanger comprising a U-shaped member provided with a base portion adapted to be imbedded in a wall, lugs bent at right angles to the sides of the hanger for engagement with the face of a wall, and anchor portions extended upwardly and rearwardly from said sides and bent at their inner ends in the direction of each other for providing anchors at points substantially above said lugs.

3. A joist hanger formed of an integral sheet of metal having a stirrup for receiving a joist with side portions extending upwardly and thence inwardly at an angle and provided with inwardly turned anchor portions 40 at their extremities, portions bent inwardly from the sides for engaging the face of a wall, and an extension on the rear side of said stirrup adapted to be imbedded in a wall, for the purpose described.

4. A device of the character described comprising in combination with a wall and a joist adapted to be supported thereon, a U shaped hanger for said joist imbedded in and anchored to said wall, and bars attached 50 to opposite sides of and connecting said joist with said hanger for tying the joist to the hanger against movement relative to the wall, said bars having end portions in interlocking engagement with the exposed sides 55 of said hanger.

5. A device of the character described comprising a hanger of U-shaped cross section having a base with a portion thereof adapted 60 to be imbedded in a wall, portions formed thereon for engagement with the face of the wall, anchors extending into said wall from the sides of said hanger, a joist carried in the hanger, and bars attached to the sides of 65 said joists and having inter-locking engage-

ment with the exposed sides of said hanger, for the purpose described.

6. A device of the character described comprising a unitary hanger having portions extending into and imbedded in a wall, and a stirrup externally of said wall, a joist carried in said stirrup, a tie bar attached to said joist, and means for irremovably connecting said tie bar with an exposed side of said stirrup when the tie bar is attached to said joist.

7. A device of the character described comprising a hanger having a stirrup externally of and adapted to engage the face of a wall, supporting portions extending from the base of the stirrup into the wall, anchor portions extending from the top of the stirrup into and adapted to be imbedded in the wall, a joist carried in said stirrup, and tie bars attached to the sides of said joist and having inter-locking engagement with the exposed sides of said stirrup, for the purpose described.

8. A device of the character described including a U shaped hanger having anchor portions adapted to be imbedded in a wall, portions formed on the sides thereof forming seats, a joist supported in said hanger, and tie bars fixed to the sides of said joist and having end portions bent at angles from the bodies of the bars and confined in said seats for tying the joists to the hanger.
